[57] CLAIM

The ornamental design for a clothing storage holder, as shown and described.

DESCRIPTION

FIG. 1 is a top, front, and right side perspective view of a clothing storage holder embodying my new design;
FIG. 2 is a rear elevational view thereof;
FIG. 3 is a left side elevational view thereof, the right side being a mirror image; and,
FIG. 4 is a bottom plan view thereof.

FIG. 4

FIG. 2

FIG. 3
